TAKE-UP FOR LOOMS

Elliot A. Santon, Worcester, Mass., assignor to
 Crompton & Knowles Loom Works, Worcester,
 Mass., a corporation of Massachusetts

Application May 1, 1943, Serial No. 485,323

10 Claims. (Cl. 139—304)

This invention relates to improvements in take-ups for looms and it is the general object of the invention to provide a take-up drive which can be operated either automatically by the loom or manually.

The cloth in a loom is led from the weaving point to a roughened take-up roll which is driven during loom operation to pull the cloth forwardly. A train of gears is connected to the take-up roll and is driven by some part of the loom at the proper rate to advance the cloth as it is woven. During normal weaving operations the take-up is driven forwardly but should a miss-pick occur necessitating removal of any picks of weft from the fabric the take-up roll is reversed so that the fell of the cloth can be moved rearwardly.

It has been proposed heretofore to operate the take-up roll by a worm wheel meshing with a worm driven by power derived from some part of the loom, such as the upright shaft of the Knowles head customarily used on worsted looms. The worm has formerly been connected to a forwardly extending take-up shaft carrying a hand wheel by which the worm and its worm wheel could be manually reversed. It is an important object of my present invention to mount the hand wheel on a sleeve carrying the worm and provide the hand wheel with a handle normally in meshing or driving relation with a driving wheel on the forward end of the take-up shaft which passes through the sleeve. The handle is constructed in such a manner as to reduce wear of itself and the part of the hand wheel which it engages.

It is another object of my present invention to provide the handle with means for pivotally connecting one end of it to the wheel and constructing the other end of the handle so that it will engage a part of the wheel and assist in holding the handle substantially fixed with respect to the hand wheel to provide an improved driving connection with the aforesaid driving wheel.

It is still a further object of my invention to provide the hand wheel with two similar pockets either of which can receive the pivoted end of the handle while the other receives the outer end of the handle. This feature of my invention permits reversal of the handle with respect to the pockets when objectionable wear has developed. No matter which pocket provides the pivotal support for the handle however the opposite pocket will receive the outer end of the handle to assist in providing a satisfactory driving connection between the shaft and the worm.

It is a more particular object of my present invention to provide a loom take-up hand wheel having diametrically opposite pockets the lower part of each of which can receive the pivoted end of the handle while the upper part of each pocket can each receive and have engagement with the outer end of the handle. By this arrangement any wear which develops in one of the pockets adjacent the pivoted end of the handle will lie below that part of the pocket which engages the outer end of the handle when the latter is reversed. The result of this construction is to cause the opposite ends of the handle to engage different parts of the pockets so that upon reversal of the handle its ends will engage unworn surfaces of the pockets.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a side elevation of part of a loom having my invention applied to the take-up thereof,

Fig. 2 is an enlarged front elevation in the direction of arrow 2, Fig. 1, showing the hand wheel and its handle in normal driving position,

Fig. 3 is a section on line 3—3 of Fig. 2 showing the handle in force transmitting position in full lines and in dotted lines for manual turning of the hand wheel and its worm, and

Fig. 4 is a transverse section on line 4—4 of Fig. 3.

Referring particularly to Fig. 1, I have shown a loom frame 10 having a pattern mechanism K driven by an upright shaft 11 and the usual gearing indicated generally at 12 for the shaft. This gearing includes a sleeve 13 which is normally down but which can be raised in the usual manner by mechanism 14. Extending forwardly from the mechanism 12 is a take-up driving shaft 15 journaled at 16 with respect to the loom frame and having the forward end thereof surrounded by a sleeve 17. A worm 18 on the sleeve meshes with a worm wheel 19 rotatable about an axis 20 and geared by mechanism not shown to the take-up roll and its train of gearing. A hand wheel 21 is provided for turning the sleeve 17 and worm 18.

The matter thus far described is of usual construction and may if desired take the form shown in the following prior patents: McGuiness 737,002; Ryon 886,871, and 1,552,651.

In carrying my invention into effect, I provide an improved driving connection between a take-up shaft 15 and the sleeve 17, this driving connection comprising a handle H mounted pivotally on the wheel 21 and movable into and out of driving connection with the shaft 17. Referring more particularly to Figs. 2 and 3, the wheel 21 has a continuous rim 25 and a hub 26 held to the sleeve 17 by a set screw 27 and connected to the rim 21 by two spokes 23. Two other spokes 30 and 31 formed in accordance with my present invention also connect the hub to the rim.

Spoke 30 has two spaced walls 32 and 33 between which extends a pocket or slot 34 which is substantially radial with respect to the axis of the wheel 21. A pivot pin 35 extends through the walls 32 and 33 and across the slot 34 at a point displaced rearwardly from the plane of rim 21, the front of the loom being at the right of Fig. 1. In similar manner the spoke 31 has spaced walls 40 and 41 separated by a pocket or slot 42 across which extends a pivot pin 43 held by the adjacent walls. The two spokes 30 and 31 and the pivot pins are substantially the same and the slots 34 and 42 are diametrically opposite.

The take-up shaft 15 has keyed thereto as at 41 a driving or clutch wheel 48 having several peripheral notches 49 each one of which is proportioned to receive a driving or clutching lug 50 on the handle H. When the parts are in the position shown in full lines in Fig. 3, the lug will be in one of the notches and as the shaft 15 turns the driving wheel 48 will turn the lug 50 and handle around the shaft axis.

The handle is formed more particularly as shown in Figs. 2 and 3 and comprises a body 55 shaped to afford a hand hold. One end of the handle is flattened as at 56 and is of such a width as to fit snugly into either of the pockets or slots 34 and 42. This end of the handle is provided with a bore 57 to receive one or the other of the pivot pins 35 and 43. Flattened surfaces 58 and 59 angularly disposed as shown in Fig. 3 are adapted for engagement with the head 60 of a spring plunger mounted in the rear part of the spokes 30 and 31 at the bottoms of the pockets or slots 34 and 42. It is to be understood that the spring plungers are similar and that one is provided for each of the slots 34 and 42. Under normal conditions one of the spring plungers will engage the surface 59 to hold the handle H in idle position, preferably within the outline of the hand wheel 21, but the handle can be moved to the dotted line position in Fig. 3 against the action of the associated spring plunger and the head of the latter will then hold the handle in proper position for manual turing of the wheel.

That end 65 of the handle H which is opposite the flattened end is of such size as to fit snugly into one or the other of the slots 34 or 42. It will be seen from Fig. 3 that the reduced end 65 engages those parts of the adjacent walls which are forward of the parts of the wall which can be engaged by the flattened part 56 of the handle.

Assuming that the parts are in the position shown in Fig. 2, the rear part of slot 34 will receive the flattened end 56 while the front part of slot 42 will engage the end 65 of the handle. The handle is therefore held firmly in the two pockets of the hand wheel, extending across its diameter and firmly placing the lug 50 in one of the driving notches 49. The driving force of the

shaft 15 is therefore transmitted from the driving wheel 48, through the lug 50 and the handle H, to the wheel 21, both ends of the handle assisting in this transmission of force. The handle end 65 reduces vibration of the flat end 56 of the handle to a minimum, but after long continued use the parts of the walls 32 and 33 which engage the handle develop wear. When this occurs the pins 35 and 43 are removed and the flat end 56 of the lever taken out of slot 34 and inserted into slot 42, after which the pin 43 is replaced to establish pivotal connection between the handle and walls 40 and 41.

Any wearing of the walls 40 and 41 in the first setting of the handle due to movement of the handle end 65 will occur at the front end of pocket 42 only, and the flattened end 56 of the handle in its new position will fit into the rear part of the slot 42 which was not previously worn by the handle end 65. In like manner, the end 65 will be located in the front end of slot 34 which did not have previous engagement with the flat end 56 of the handle. The handle in its new setting therefore engages surfaces which it did not engage in its previous setting. The lug 50 will be able to fit into one or another of the notches 49 when the handle is thus reversed.

From the foregoing it will be seen that I have provided an improved hand wheel and handle serving as a drive between the shaft 15 and the worm 18 so constructed that the handle H when in normal position engages opposite sides of the wheel to drive the latter uniformly and prevent jarring and objectionable motion between the pocket walls and the ends of the handle. It will also be seen that the handle is reversible due to the construction and proportions of its ends and that the lug 50 will have driving relation with respect to the drive wheel 48 when the handle is in either of its positions. Furthermore, it will be noted that the flattened end 56 engages the rear parts only of the pockets 34 and 42 whereas the handle end 65 engages the forward parts only of said pockets, hence the wear produced by one end of the handle in the pocket does not interfere with the proper fit of the other end of the handle when the latter is reversed.

Having thus described my invention it will be seen that changes and modifications may be made therein by those skilled in the art without departing from the spirit and scope of the invention and I do not wish to be limited to the details herein disclosed, but what I claim is:

1. In take-up mechanism for a loom having a take-up shaft provided with a clutch member and having a hand wheel, means on the wheel defining diametrically oppositely disposed pockets, a handle having one end located in one of said pockets and pivoted to the hand wheel, the handle extending across said wheel and normally having the other end thereof located in the other of said pockets in driving engagement with said wheel, and a clutch lug on said handle for movement by the handle into and out of clutching relation with respect to said clutch member as the handle pivots on the wheel.

2. In take-up mechanism for a loom having a take-up shaft provided with a clutch member and having a hand wheel, two pairs of spaced walls on said wheel, one pair being diametrically opposite the other pair, a handle having one end thereof pivoted to one of said pairs of walls and located between the latter, the handle extending across said wheel and having the other end thereof located between and normally having driving

relation with the other pair of walls, and a clutch lug on said lever movable into and out of driving relation with respect to said clutch member by movement of the handle pivotally with respect to the wheel.

3. In take-up mechanism for a loom having a take-up shaft provided with a clutch member and having a hand wheel, means carried by opposite sides of the wheel to provide similar pivotal supports, a handle capable of having two different driving relations with respect to the wheel and having one end adapted for mounting on either of said pivotal supports, one at a time, and having the other end thereof extending across the wheel and located normally in driving relation with the side of the wheel opposite to the side on which the handle is pivoted, and a clutch lug on the handle movable into and out of driving relation with said clutch member by pivotal movement of the handle about whichever support is serving as pivotal support for said handle.

4. In take-up mechanism for a loom having a take-up shaft provided with a clutch member and having a hand wheel, means on said wheel defining diametrically opposite pockets of substantially the same width extending in the direction of the axis of the wheel, a handle reversible with respect to said pockets and having one end thereof of a thickness substantially the same as the width of said pockets and provided with means for pivotal support and having the other end thereof of substantially the same thickness as the width of said pockets, means to mount the first named end of the handle pivotally in either pocket, the handle extending across the wheel and having said other end thereof located in the other pocket and having driving relation with said wheel, and a clutch lug on said handle movable into and out of clutch relation with respect to said clutch member by pivotal movement of the handle relative to the wheel.

5. In take-up mechanism for a loom having a take-up shaft provided with a clutch member and having a hand wheel, walls located on diametrically opposite sides of the wheel, a handle reversible relatively to the wheel and having a clutching lug for cooperation with the clutch member, means to support one end of the handle pivotally on either of said walls, one at a time, so that the other end of the handle extends into driving engagement relatively to the other wall, and means to hold said handle in normal operating position with the lug in driving relation with respect to the clutch member and so that the opposite ends of the handle engage parts of the walls located at different points measured in a direction parallel to the axis of the wheel, whereby upon reversal of the handle the ends thereof will engage parts of the wall not engaged by the handle in the previous setting thereof.

6. A hand wheel for a loom take-up shaft having a clutch member, similar walls on diametrically opposite sides of the wheel, a reversible handle for the wheel having a lug to engage the clutch member in either of the two operative positions which the handle can have relatively to the wheel, and means associated with each wall to provide a pivotal support for one end of the

handle, each of said means when operatively related to said one end of the handle locating the other end of the handle in driving relation with the wall corresponding to the other of said means.

5 7. A hand wheel for a loom take-up shaft having a clutch member, said wheel having a pair of diametrically opposite pivotal supports and a driven surface for each pivotal support, a handle having one end thereof capable of mounting on either support, said supports, driven surfaces and handle being so proportioned and located that when said one end of the handle is mounted on either of the pivotal supports the other end of the handle has driving relation with the driven surface corresponding to the other pivotal support, and a clutch lug on the handle for said clutch member.

10 8. A hand wheel for a loom take-up shaft having a clutch member, said wheel having a pair of diametrically opposite pivotal supports and a driven surface for each support, a handle having one end thereof capable of mounting on either pivotal support, means to hold the handle when on either support with the other end thereof in engagement with the driven surface corresponding to the other pivotal support, and a clutch lug on the handle for said clutch member, said pivotal supports located in a plane perpendicular to the axis of the wheel and spaced from a plane perpendicular to the said axis and passing through said driven surfaces engageable with said other end of the handle.

20 9. A hand wheel for a loom take-up shaft having a driving member, a reversible handle capable of assuming two different positions with respect to the wheel, diametrically opposite pivotal supports on the wheel to receive one end of the handle, one pivot at a time, diametrically opposite walls on the wheel, one for each pivotal support, to engage the other end of the handle, a clutch lug on the handle for the clutch member, and means to hold the handle when on either pivotal support in extended position across the wheel with said other end of the handle in engagement with a part of the wall on the opposite side of the wheel which is spaced in the direction of the wheel axis from the associated pivotal support.

25 10. A hand wheel for a loom take-up shaft having a driving member, a reversible handle capable of assuming two different positions with respect to the wheel, diametrically opposite pivotal supports on the wheel to receive one end of the handle, one pivot at a time, diametrically opposite walls on the wheel, one for each pivotal support, to engage the other end of the handle, a clutch lug on the handle for the clutch member, and a spring plunger to hold the handle across the wheel and maintain said other end of the handle in engagement with the wall on the opposite side of the wheel with the clutch lug positioned for engagement with the clutch member, said spring plunger holding the handle so that the pivotal support thereof and part of the wall engaged by the other end of the handle are displaced longitudinally with respect to the axis of the wheel.

ELLIOT A. SANTON.
